(57) **CLAIM**

I claim the ornamental design for a electric vehicle recharging terminal with screen display, as shown and described.

DESCRIPTION

FIG. 1 is a front right perspective view of a first embodiment of an electric vehicle recharging terminal with screen display showing my new design;

FIG. 2 is a rear right perspective view thereof;

FIG. 3 is a front left perspective view thereof;

FIG. 4 is a rear left perspective view thereof;

FIG. 5 is a front right perspective view of a second embodiment of an electric vehicle recharging terminal with screen display showing my new design;

FIG. 6 is a rear right perspective view thereof;

FIG. 7 is a front left perspective view thereof;

FIG. 8 is a rear left perspective view thereof;

FIG. 9 is a front right perspective view of an alternative embodiment of the electric vehicle recharging terminal with screen display of FIGS. 5-8 showing my new design;

FIG. 10 is a rear right perspective view thereof;

FIG. 11 is a front right perspective view of an alternative embodiment of the electric vehicle recharging terminal with screen display of FIGS. 1-4 showing my new design; and,

FIG. 12 is a rear right perspective view thereof.

The rectangular regions in the figures shown in the upper portion of the electric vehicle recharging terminal represents a computer screen display for displaying graphical information and images. The unshown bottom of the electric vehicle recharging terminal with screen display forms no part of the claimed design.
